CLAIM

The ornamental design for a time recorder, as shown and described.

DESCRIPTION

FIG. 1 is a front perspective view of a time recorder showing our new design;

FIG. 2 is a rear perspective view thereof;

FIG. 3 is a front view thereof;

FIG. 4 is a rear view thereof;

FIG. 5 is a left side view thereof, the right side view being a mirror image thereof;

FIG. 6 is a top view thereof; and,

FIG. 7 is a bottom view thereof.

The dashed broken lines illustrate environmental structure and form no part of the claimed design.

The dot-dash broken lines, in FIGS. 1 and 3, represent an unclaimed boundary between claimed and unclaimed portions.

The drawings include surface shading which represents contour, not surface ornamentation.
